BROOCH OR SIMILAR ARTICLE

Jacques Martial, Great Neck, and Lincoln L. Ciampa, New York, N. Y., assignors to United States Electric Mfg. Corp., New York, N. Y., a corporation of New York

Application November 27, 1951, Serial No. 17,533

Term of patent 14 years

(Cl. D45—19)

To all whom it may concern:

Be it known that we, Jacques Martial and Lincoln L. Ciampa, both citizens of the United States, residing at Great Neck, in the county of Nassau, city and State of New York, and Borough of Manhattan, in the county of New York, city and State of New York, respectively, have invented a new, original and ornamental Design for a Brooch or Similar Article, of which the following is a specification, reference being had to the accompanying drawing, forming part thereof.

In the drawing:

Fig. 1 is a front view of a brooch, showing my new design;

Fig. 2 is a rear view of the brooch;

Fig. 3 is a view of one side of the brooch; and Fig. 4 is a view of the other side of the brooch.

We claim:

The ornamental design for a brooch or similar article, substantially as shown.

JACQUES MARTIAL.
LINCOLN L. CIAMPA.
